UNITED STATES PATENT OFFICE.

JOHN MILLER SAUDER, OF PHILADELPHIA, PENNSYLVANIA; EXPERIENCE L. SAUDER ADMINISTRATRIX OF SAID JOHN MILLER SAUDER, DECEASED.

ADJUSTABLE SCHOOL DESK AND SEAT.

SPECIFICATION forming part of Letters Patent No. 688,267, dated December 3, 1901.

Application filed December 31, 1897. Serial No. 664,864. (No model.)

To all whom it may concern:

Be it known that I, JOHN MILLER SAUDER, of Philadelphia, in the county of Philadelphia and State of Pennsylvania, have invented a new and Improved Adjustable School Desk and Seat, of which the following is a specification.

My invention is an improvement in the class of school desks and seats which are adjustable vertically to accommodate pupils of different heights. As to one of its more important features it is an improvement in that particular class of desks and seats which are provided with longitudinally-slotted standards made in one continuous piece and pinions, racks, and nuts for adjusting the desks and seats proper vertically and for locking them in any adjustment from either side of desk or seat. I have simplified and reduced the number of parts heretofore required to effect such adjustment, have made a new and better arrangement of the same, and produced a mechanism capable of a more easy and speedy adjustment.

Another important feature is the construction of the desk-standards, whereby they occupy less floor-space and furnish a support for the chair-seat in front of the desk.

These and other features are hereinafter described with the necessary detail.

In the accompanying drawings, (two sheets,) Figure 1 is a side elevation of my improved desk and seat supports. Fig. 2 is an enlarged detail side view of a portion of one of the standards and brackets. Fig. 3 is an enlarged perspective view of some of the parts used for clamping the standards to the desk and adjusting the latter. Fig. 4, Sheet 2, is a horizontal section on line 4 4 of Fig. 1. Fig. 5 is an enlarged horizontal section on line 5 5 of Fig. 1. Fig. 6 is an enlarged sectional side view of a portion on line 6 6 of Fig. 5. Fig. 7 is a side view of a modified form of standard having no connection with a seat. Fig. 8 is a cross-section on line 8 8 of Fig. 7.

The two legs or standards 1 are separate from the desk proper, 2. The shelf 3 of the latter is secured between side brackets 4 and all firmly connected. Each leg or standard 1 is in one continuous length from floor to side or end of book-box and is provided in its up-

per portion with a lengthwise slot 5 and on the inner side, Fig. 6, with an integral rack 6, which is adjacent and parallel to said slot. Each standard 1 is further provided with one or more, preferably two, lengthwise ribs 7, which are parallel and arranged on opposite sides of the slot 5 and adapted to fit and work in corresponding grooves 8, Figs. 2 and 5, formed in the inner side of the pendent wings 9 of the brackets 4. The ribs 7 are conical or wedge shaped and made wider than the grooves 8, so that the ribs will wedge or fit closely into the grooves under all circumstances without contact with the bottoms of the grooves, and thus insure a rigid connection between the standards and desk proper.

The means for clamping the slotted ends of the standards 1 and 1 to the brackets 4 are a tube or rod 10 and the nuts 11, applied to the latter and screwing against washers 12, interposed between them and the outer sides of the standards. The said washers 12 have a spline connection 13 with the tube 10, so that they must rotate together.

It is apparent that by rotating either nut 11 in one direction the standards 1 will be clamped tightly upon the brackets 4 and the desk 2 thus held firmly and rigidly supported between them, and by rotating either nut 11 in the opposite direction the clamp will be released, and the desk 2 may then be adjusted higher or lower, as required. It will be understood that this operation is rendered practicable by reason of the fact that when a nut 11 is thus rotated the other and opposite nut will remain fixed on the tube 10 because its washer 12 prevents friction between the nut and the adjacent standard. Hence practically it is only necessary to operate one nut 11 to clamp the desk 2 between the standards 1 or to release the same. The nuts 11 are preferably made in the form of truncated ribbed cones having an axial bore, and a suitable wrench is provided for the same.

The means for vertical adjustment of the desk 2 on the standards 1 are the pinions 14, Figs. 3 and 6, which engage the aforesaid racks 6, as shown. Such pinions have a spline connection 15 with the tube 10 and rotate with it. It is therefore obvious that by rotating the tube 10 the pinions 14 will travel

- up or down the racks 6 and carry the desk 2 higher or lower, as desired. As a means for thus rotating the tube 10 I employ a crank-wrench 15, having a slotted end 16, which is 5 adapted to enter either end of the tube 10 and engage a cross-pin 17 thereon. While this is the simplest form of construction, it is obvious the wrench might be adapted to enter a polygonal or other irregular socket 10 formed in the ends of the tube. In any case the essential feature is the adaptation of the wrench for insertion through the nuts 11 and for operation independently of the nut-wrench or simultaneously therewith, as required. It is apparent that one of the nuts 11 must be turned to clamp the desk 2 directly an adjustment of the desk has been effected by rotating the tube 10 and rack-pinion 14.
- 20 It will be noted as an important feature of my invention that the standards being slotted at their upper ends the clamping-tube 10 will be located directly beneath the book-shelf 3 of the desk, and hence the space beneath the shelf is left entirely free for unobstructed movement of the pupil's legs as well as for use of a broom or mop for cleaning purposes. It will be further noted that the slotted ends of the standards 1 overlap the 25 sides of the desk proper and that they maintain such relation whether the desk be adjusted higher or lower.
- The feet 18 of the main body of the standards 1 are extended a little rearward; but 30 the front portions or legs 1^a are extended forward and also curved inward toward each other and are provided near their ends with downwardly and forwardly extending feet 19, as shown in Figs. 1, 4, and 7. The 35 branches or arms 1^b of such converging portions 1^a are clamped upon the flat standard 21, to which a chair-seat 22 is secured. Such chair-standard 21 may be adjustably and otherwise connected with the branches or 40 arms 1^b by means of a threaded tube, nuts, pinion, and rack, as in the case of the standards 1 and desk 2, before described, or any other suitable means of adjustment may be adopted.
- 45 It will be seen that by arranging the front legs and feet of the standards convergently, as shown, less floor-space is occupied, and thereby the standards are firmly braced from the floor in all directions—that is to say, 50 against movement or displacement of the desk by pressure applied on any side.
- In Figs. 7 and 8 I illustrate a simple form of standard 1^x, which embodies the same principle of construction and arrangement of 55 branch legs 22, the latter being extended forward and curved inward, so as to occupy less floor-space and be out of the way, while affording a very firm and rigid brace from the floor.
- 60 It will be noted that the standards 1 and their slots are inclined rearward, so that as

the desk is raised or lowered it will be carried farther from or brought nearer to the pupil, and thus made to accommodate its position to his size, but can be made from a vertical to any direct inclination.

I desire it understood that while I prefer to make the ends of the desk or book-box proper of metal open-work, as shown for simplicity of construction and compactness in shipment in 75 "knockdown" shape, I may use wooden ends in place thereof and attach pendent metal brackets to the lower edge and side of the same to serve as bearings for the tube or rod and also to contain the grooves necessary for 80 engagement with the ribs of the standards.

In adjustable desks as heretofore made wooden ends were employed to form the book-box and the standards were made in two pieces sliding against each other and connected by bolts near the center of the lap or splice, the upper part of the standard being secured to the under side of the book-shelf, which in that case always required a thickness of one-inch stock lumber, so as to hold 90 the screws. Their standards being made in two parts or pieces, it was impracticable to use a connecting-rod for raising the desk uniformly at both ends by gear, since the rod passing from one standard to the other half-way between floor and desk would always be in the way of the legs of the pupil and also in the way for sweeping and cleaning the floors. I have overcome these serious defects and objections by making the upper sliding part the 100 end of the book-box and making the standard in one continuous or unbroken piece, with a slot at the extreme upper end, thereby enabling me to give an adjustment to the desk the full depth of the book-box. The standards 105 sliding up and down by the side or ends of the book-box, the connecting tube or rod may be placed entirely out of the way and at the same time assist in clamping together, and thereby strengthening, the book-box, always keeping 110 the book-shelf locked firmly and securely in place, and at the same time producing the simplest and easiest method of adjustment, avoiding the necessity of passing from one 115 side of the desk to the other to release a nut or two on each side independent of the other and then back and forth again to tighten up the same when at last properly adjusted. In my adjustment there is no reason for disturbing the pupil in the least. The operator can 120 pass up and down any aisle and adjust two rows of desks from the same aisle without any interference with the school routine.

A tube has advantages in that it is stiffer than a rod of like weight in rotating for raising or lowering the desk and also makes it easier to form a crank attachment for adjusting the desk. With a rod or bolt the desk can readily be raised or lowered by hand by raising or lowering one end, the opposite end 125 being obliged to follow on a parallel or level line. By making the standards in one con-

tinuous piece and narrow instead of broad more space is afforded for the pupil getting in and out.

What I claim is—

- 5 1. The combination with a desk-body provided with depending side brackets having vertical grooves in their outer faces, of standards having slotted upper end and provided with racks at one side of the slots and with 10 tongues on their inner faces working in the grooves of the brackets, a tube journaled in the brackets directly beneath the desk-body and having its ends screw-threaded and projecting through the slots of the standards, 15 nuts on the ends of the tube, pinions splined to the tube and arranged on the inner side of the standards, and washers also splined to the tube and arranged between the nuts and standards, substantially as described.
- 20 2. The combination, with the desk or seat, having brackets with internal grooves, of standards slotted as specified, and having one or more truncated or flattened ribs, which are adapted to wedge in such grooves, and the

screw-threaded tube or rod and nuts applied 25 thereto, for clamping the desk between the standards as shown and described.

3. The combination with a desk or seat provided with brackets, and slotted standards having racks as specified, of an open-end tube 30 passing through said brackets and the slots of the standards, axially-bored nuts applied to the ends of said tube, and pinions splined with the latter, the said tube being adapted to receive a wrench for engaging and rotating the same, as shown and described.

4. An adjusting mechanism for furniture comprising standards formed with a rack, and a slot; a shaft provided with a socket at its end; the ends of said shaft projecting through 40 said slot and being screw-threaded on the exterior, to receive clamping means; pinions on said shaft adapted to engage said racks; and said clamping means.
